UNITED STATES PATENT OFFICE.

CHARLES F. PRESTON, OF CHICAGO, ILLINOIS.

TOOL-HOLDER.

SPECIFICATION forming part of Letters Patent No. 699,708, dated May 13, 1902.

Application filed July 25, 1901. Serial No. 69,704. (No model.)

To all whom it may concern:

Be it known that I, CHARLES FRUIN PRESTON, a citizen of the United States, and a resident of Chicago, in the county of Cook and 5 State of Illinois, have invented a new and Improved Tool-Holder, of which the following is a full, clear, and exact description.

The object of the invention is to provide a new and improved tool-holder especially designed for use in lathes, planers, and other metal-working machines and arranged to adjustably hold a cutting-tool with an even bearing on the top and bottom to prevent undue vibration and render the tool as solid as an 15 ordinary forged-steel tool.

Another object of the invention is to adjustably hold the tool in the holder without the use of set-screws or other objectionable projections liable to interfere with the proper 20 handling of the tool in the machine.

Another object of the invention is to provide a tool having no projections to interfere with the tool being removed or replaced in the tool-post.

25 The invention consists of novel features and parts and combinations of the same, as will be fully described hereinafter and then pointed out in the claims.

A practical embodiment of the invention 30 is represented in the accompanying drawings, forming a part of this specification, in which similar characters of reference indicate corresponding parts in all the views.

Figure 1 is a side elevation of the improvement. Fig. 2 is a sectional side elevation of the same. Fig. 3 is a plan view of the same. Fig. 4 is a transverse section of the same on the line 4 4 in Fig. 1, and Fig. 5 is a similar view of the same on the line 5 5 in Fig. 1.

40 The improved tool-holder consists, essentially, of a shell or casing A, in which is mounted to move a locking-slide B, adapted to lock a cutting-tool C in position in the casing or shell A at one end thereof, with an even bearing on the top and bottom of said cutting-tool. The slide B fits snugly in the opening A' of the casing A, with the exception of the front end, which is somewhat reduced, and formed on the top with a bevel B', extending 45 inwardly and downwardly, as is plainly indicated in Figs. 1 and 2. On this bevel rests the under side of the cutting-tool C, which

engages with its top a bevel A², corresponding to the bevel B' and formed on the upper wall of the opening A', as is plainly shown 55 in Figs. 1 and 2. It is evident that when the cutting-tool C is placed on the slide B at the bevel B' thereof and at the time when the said slide B is in an outermost position, as shown in Fig. 2, then upon driving the slide inward 60 the tool C is forced upward by the bevel B' against the bevel A², so that the tool C is securely locked in position in the holder between the two bevels B' and A² of the slide B and the casing A. When this has been done, a 65 set-screw D, screwing through the top of the casing A against a bevel B² in the slide B, serves to lock the latter in an innermost locking position. (See Figs. 1 and 5.) The head of the set-screw D extends into a recess in 70 the top of the casing A, so as not to project from the same. The casing A has a cross-section corresponding approximately to that of the ordinary forged-steel tool and is, like the latter, set and fastened in the tool-post or 75 other device ordinarily employed for carrying the tool.

By the arrangement described the tool C is adjustably held in the holder and an even bearing is had on the tool, so as to prevent 80 undue vibration, and thereby render the tool as solid as an ordinary forged-steel tool.

Having thus fully described my invention, I claim as new and desire to secure by Letters Patent—

1. A tool-holder, comprising a casing, a slide movable in said casing and adapted to project at its forward end therefrom, the said forward end of the slide being reduced and formed with a beveled top for engaging the 90 tool and pressing the same against a correspondingly-beveled wall of the casing, as set forth.

2. A tool-holder, comprising a casing, and a slide having a rectangular body portion 95 fitted in the opening of the casing, the forward end of said slide being reduced and the top of said reduced portion being beveled inward and downward, opposite a corresponding bevel in the top wall of the casing, the 100 said reduced end of the slide being adapted to be moved into an outermost position to permit of the insertion of a tool between said beveled surfaces, as set forth.

3. A tool-holder, comprising a casing, a slide movable in the casing, one face of said slide at one end being beveled inward opposite a corresponding bevel in the wall of the
5 casing, and a set-screw extending through the wall of the casing and engaging the slide.
4. A tool-holder, comprising a casing, a slide movable therein, the slide having one end reduced, the top of the reduced portion
10 being beveled inward and downward opposite a corresponding bevel in the top wall of

the casing, and a set-screw screwing in the casing against the bevel on the slide, to lock the latter in place after adjustment is made, as set forth.

15

In testimony whereof I have signed my name to this specification in the presence of two subscribing witnesses.

CHARLES F. PRESTON.
